CLAIM

The ornamental design for a waste bin, as shown and described.

DESCRIPTION

FIG. 1 is a perspective view of the waste bin;
FIG. 2 is a front view of the waste bin shown in FIG. 1;
FIG. 3 is a rear view of the waste bin shown in FIG. 1;
FIG. 4 is a right side view of the waste bin shown in FIG. 1, the left side being a mirror image thereof; and,
FIG. 5 is a top view of the waste bin shown in FIG. 1.
The broken lines in the drawings are included for the purpose of illustrating portions of the 'article' and form no part of the claimed design.
